EDWARD E. MASTON, OF WILMETTE, ILLINOIS, ASSIGNOR TO CONTAINER CORPORATION OF AMERICA, OF CHICAGO, ILLINOIS, A CORPORATION OF DELAWARE

PACKING CASE

Application filed June 8, 1928. Serial No. 283,895.

This invention relates to packing cases for fragile articles and more particularly to articles such as glass and porcelain electric light fixtures. One object of the invention is to provide a packing case of a very light but rigid construction, having a maximum resistance against crushing or collapsing strains. Another object of the invention is to provide a packing case in which articles may be quickly and securely packed with a minimum of time and effort by inexperienced persons. A further object of the invention is to provide a packing case of extremely simple design, comprising a minimum number of parts with a maximum of strength and rigidity. To these and other ends the invention resides in certain improvements and combinations of parts, all as will be herein-after more fully described, the novel features being pointed out in the claims at the end of the specification.

In the drawings:

Fig. 1 is a perspective view of a packing case embodying the present invention, certain parts being broken away for the purposes of clearness;

Fig. 2 is a detail view of the end or closure member for the inner shell;

Fig. 3 is a fragmentary sectional view illustrating the manner of packing one type of light shade in the case, and

Fig. 4 is a fragmentary perspective view of a somewhat modified form of the invention.

Similar reference numerals throughout the several views indicate the same parts.

The present embodiment of the invention provides a container or case of the class described having a light, strong and rigid construction and capable of being rapidly and economically manufactured and assembled, being particularly advantageous for packing fragile articles such as lamp shades or reflectors which may or may not be capable of being partially nested. To this end the invention, as disclosed, is embodied in an outer container and a shell spaced therewith in, such shell being provided with means for supporting one or more fragile objects in a safe and secure manner.

Referring more particularly to the draw-

ings, there is shown in Fig. 1 an outer container 5 of more or less usual form which may be constructed from any suitable material, but which, in the present instance, is illustrated as formed of corrugated paper. The container 5 is provided with the usual closure flaps 6, 6. Within the container 5 is provided a shell 8 preferably formed of light fibrous material such as corrugated paper or solid fibre board. The shell 8 is preferably constructed from a flat rectangular blank suitably provided with score lines 9, 9 along which it may be bent to provide a polygonal shell. In the present instance, the shell is creased or scored so as to form an octagonal figure, the number of sides which the shell has, however, is, in general, immaterial.

The shell 8 is provided at each end with a closure member or plate, one of which is designated at 10, see Figs. 1, 2 and 3. If it is desired to pack shades of the shape illustrated in Fig. 3 in nested relation within the shell 8, there will also be provided a plurality of partition members 11, 11. Where it is desired that the case contain but a single article, such as a large spherical globe, these partition members will not be used.

The end plates or closures 10 are preferably so associated with the inner shell as to serve as reinforcing and stiffening means for said shell, and also to provide spacing means for maintaining said shell spaced within the outer container and at the same time serving to firmly secure said closure in place at the end of the shell. This may be done in various ways but in the present instance the sides of the shell 8 are preferably provided with slots 12 through which tongues or extensions 13, 13 on the plate 10 may be inserted. The blank comprising the closure plate 10 is preferably of such a size that, when the parts are assembled and the tongues 13 project through the slots in the inner shell, the ends of the tongues will abut the inner surface of the outer container to thus firmly hold the shell spaced therewithin. Thus the closure plate 10 with its tongues 13 serves the double purpose of closing the end of the shell and

maintaining the shell spaced within the outer container.

In order to increase the rigidity of the assembled inner shell and closure plate 10, the latter is preferably provided with a plurality of flaps or tongues 14, 14, spaced alternately between the tongues 13, 13 and provided with score lines 15 by means of which they may be readily bent at right angles to the plate so as to lie against or abut the inner face of the inner shell when the parts are assembled. While the tongues 14 may extend in either direction, they are preferably arranged so as to extend toward the adjacent outer ends of the shell, and are of such length as to substantially register with the end of the shell. The flaps or tongues 14 are preferably of a width corresponding to the distance between the score lines 9, 9 of the inner shell, see Fig. 1. These flaps or tongues, however, may be made of less width if desired.

One of the meeting edges of the blanks, forming the inner shell, is provided with a short extension 16 which overlaps the adjoining side of the shell. These overlapping ends may, if desired, be secured together, after packing the shades therein, by means of ordinary gummed tape in a manner which is well understood.

When it is desired to pack bowl-shape shades or reflectors in the case, such as shown in Fig. 3, the partition members 11, 11 are preferably employed. These partition members are each provided with tongues 17, similar to tongues 13, which project through additional slots 12, 12 formed in the sides of the inner shell. The partition members may or may not be provided with bent-over tongues or extensions, such as tongues 14 of the closure plate 10. In the present instance, such tongues or flaps are preferably dispensed with.

In order that a maximum number of shades may be packed within the case, the partitions 11, as well as one of the closure plates 10, are provided with a central aperture 18 through which the smaller part of the shade may be inserted so that the shades may be partially nested, as clearly shown in Fig. 3.

For the purpose of permitting close engagement of the edges of the apertures 18 with the small parts of the shades, there is preferably provided at each aperture 18 a plurality of short radial slits forming a plurality of inwardly extended tongues 18a. These tongues are capable of being bent when the flanged end of the shade is being inserted within the aperture 18 and will return substantially to the plane of the closure or partition when the flanged part has been inserted so that the inner edges of the tongues contact at or near the juncture of the restricted end of the shade with the bowl-shaped body portion.

The shades are thus firmly but yieldingly supported at a multiplicity of points but without engaging one another, as may be readily seen. Due to the engagement of the smaller end of the shade within the aperture 18 in one of the partitions, the shade is held from lateral shifting movement as well as from end-wise or axial movement in one direction. The larger end of the shade rests on or contacts with an adjacent partition 11 and its outer surface is engaged laterally at a number of points by the sides of the inner shell 8. It will be seen by reference to Fig. 3, that the upper portion of the uppermost shade is spaced a sufficient distance from contact with the closure flaps 6, 6 to avoid breakage of the shade by reason of any inward flexing of the closures due to heavy objects piled thereon in shipment.

In the modified form of the invention, disclosed in Fig. 4, there is provided an outer container 20, similar to container 5, and an inner shell 21, shown in this embodiment as formed with four sides instead of eight as in the case of the inner shell 8. An end plate or closure 22, also of generally rectangular form, is assembled with the shell 21 by means of tongues 23 integral with the plate 22 which project through suitable slots in the sides of the shell 21, such slots and tongues being disposed centrally of the sides of the shell and considerably narrower than such sides.

In this embodiment of the invention, the end plate or closure 22 is provided with tongues or flaps 24, 24 which are disposed adjacent and on each side of the corner thereof so that when bent at right angles to plate 22 they fit against or abut the inner face of shell 21 on each side of its corners. These tongues or flaps, similar to tongues or flaps 14, are preferably disposed, when the parts are assembled, to extend outwardly toward the ends of the shell and are preferably of such a length when assembled as to coincide or register with the end of said shell. There is thus obtained a maximum of strength and rigidity at points where the container is most likely to be deformed or crushed by heavy objects being placed thereon. This form of the container may also, if desired, be provided with partition members in a manner similar to that shown in the first embodiment, these partition members, of course, being of rectangular form similar to the end plates 22. In a similar manner as described in the first embodiment of the invention, the partitions and one end plate may be provided with apertures for the reception of the small ends of the shades being packed therein.

The assemblage and use of this form of the invention is practically identical to that of the first form so that further detailed explanation of such is unnecessary.

The present invention thus provides an

extremely simple packing case for fragile articles comprising few parts but which are associated in such a manner as to obtain a maximum of strength and rigidity for a

5 minimum amount of material employed. By means of the case disclosed herein articles such as lamp shades or reflectors may be rapidly and safely packed for shipment without necessitating the use of excelsior or

10 other packing material.

The resiliency of the inner shell alone is sufficient to prevent any but the most severe shocks being transmitted to the articles therewithin.

15 Having described my invention, I claim:

1. In a packing case, the combination with an outer container and an inner shell, of a member forming a closure for said shell, slots in said shell, and tongues on said closure 20 projecting through said slots and engaging the outer container to hold said shell spaced therewithin.

2. In a packing case, the combination with an outer container and an inner shell, of a 25 member forming a closure for said shell, means for securing said closure to said shell and for spacing said shell within said container, said means comprising tongues on said closure abutting the inner walls of said 30 outer container, and additional tongues intermediate said first named tongues and adapted to be bent over to abut the interior of said shell.

3. In a packing case, the combination with 35 an outer container and an inner shell, of a member forming a closure for said shell, slots in said shell, tongues on said closure projecting through said slots and engaging the outer container to hold said shell spaced 40 therewithin, and additional tongues on said closure lying intermediate the first named tongues and adapted to be bent at an angle to the plane of said closure to lie against the inner face of said shell.

45 4. In a packing case, a tubular shell, a member forming a closure for said shell, slots in said shell, tongues on said closure projecting through said slots, and additional 50 tongues intermediate said first named tongues adapted to be bent at right angles to said closure to abut the interior of said shell.

5. In a packing case, a tubular shell, a member forming a closure for said shell, slots in said shell, tongues on said closure projecting through said slots, and additional 55 tongues intermediate said first named tongues and adapted to be bent outwardly of said shell to abut the inner wall thereof, said last mentioned tongues being of such a length 60 as to substantially coincide with the end of said shell.

6. In a packing case, a tubular shell, a member forming a closure for said shell, means for securing said closure in place with- 65 in and spaced from the end of said shell, and

tongues on said closure adapted to be bent at right angles thereto to abut the interior of said shell whereby the rigidity of said shell is increased.

EDWARD E. MASTON.
